UNITED STATES PATENT OFFICE.

FRANK KUHN, OF DETROIT, MICHIGAN, ASSIGNOR TO AMERICAN ELECTRICAL HEATER COMPANY, OF DETROIT, MICHIGAN, A CORPORATION OF MICHIGAN.

DESIGN FOR A CURLING-IRON HEATER.

46,504.

Specification for Design.

Patented Oct. 6, 1914.

Application filed July 9, 1914. Serial No. 850,023. Term of patent 14 years.

To all whom it may concern:

Be it known that I, FRANK KUHN, a citizen of the United States of America, residing at Detroit, in the county of Wayne and State of Michigan, have invented a certain new, original, and ornamental Design for Curling-Iron Heaters, of which the following is a specification, reference being had therein to the accompanying drawings, forming part thereof, in which the figure is

a perspective view of a curling-iron heater, showing my new design.

I claim:

The ornamental design for a curling iron heater, substantially as shown.

FRANK KUHN.
